**METHOD FOR THE RECOVERY OF TAR ACIDS
BY EXTRACTION IN THE PRESENCE OF AN
ALKALI SOLUBLE HYDROSULFITE**

Calvin Columbic, Pittsburgh, Pa., assignor to the United States of America as represented by the Secretary of the Interior

No Drawing. Application April 19, 1952,
Serial No. 283,236

5 Claims. (Cl. 260—627)

(Granted under Title 35, U. S. Code (1952), sec. 266)

The invention herein described and claimed may be 15 manufactured and used by or for the Government of the United States of America for governmental purposes without the payment of royalties thereon or therefor.

This invention is concerned with an improved method for the recovery of tar acids.

In the recovery of tar acids from the products of the carbonization or the hydrogenation of coal or from petroleum and similar materials, the basic step in the recovery procedure is the extraction of the tar acid-containing material with an aqueous caustic solution. After extraction, the tar acids are "sprung" by acidification of the extract and then subjected to the usual purification procedures. Oftentimes, tar acids obtained by this procedure are highly colored and possess an undesirably high viscosity. Apparently, darkening and high viscosity are the result of side reactions occurring during the caustic extraction. These undesirable effects are particularly apparent in the recovery of tar acids from low temperature tars produced by the low temperature carbonization of coal, lignite, and the like. With this type of material, furthermore, serious loss of potentially recoverable tar acids often occurs owing to the precipitation of resinous, and insoluble material during the caustic extraction.

In accordance with the present invention, it has been found that undesirable side effects occurring during caustic extraction which often lead to darkening, increased viscosity, and diminished yields, can be substantially mitigated or entirely prevented by conducting the extraction in the presence of a relatively small amount of an alkali soluble hydrosulfite, preferably an alkali metal hydrosulfite such as sodium hydrosulfite, $\text{Na}_2\text{S}_2\text{O}_4$. Most desirably, the alkali soluble hydrosulfite is added to the aqueous caustic solution employed as the extractant which contains usually from 5% to 20% of a strong alkali such as NaOH or KOH . The amount of hydrosulfite required will depend upon the material being extracted, more or less being necessary depending upon the tendency of the material to undergo reactions which lead to darkening and other undesirable side effects. The minimum amount necessary in any particular case can be determined by simple experiment. In most cases, a relatively small amount of the order of 2% to 3% based upon the weight of the caustic solution employed as the extractant will be found satisfactory.

Alkali soluble hydrosulfites suitable for use in accordance with the invention include, for example, alkali metal hydrosulfites such as sodium hydrosulfite $\text{Na}_2\text{S}_2\text{O}_4$, potassium hydrosulfite $\text{K}_2\text{S}_2\text{O}_4$, as well as ammonium hydrosulfite $(\text{NH}_4)_2\text{S}_2\text{O}_4$. Sodium hydrosulfite is to be preferred for its cheapness and availability. While the action of the hydrosulfites in preventing the undesirable effects discussed above is not completely understood, it is believed that these materials prevent the oxidation and subsequent polymerization of such compounds as dihydric phenols which are present in the mixture being extracted. It is to be understood however, that the invention does not depend upon this, or any other particular theory as

2

to the ultimate explanation of the beneficial effects produced.

While the efficacy of the hydrosulfites is probably due at least in part to their reducing properties, it has been found that other similar reducing agents such as sodium sulfite, Na_2SO_3 , and sodium bisulfite, NaHSO_3 , are ineffectual in preventing the undesirable side effects of alkali extraction. These other relatively strong reducing agents such as sodium sulfoxylate $\text{H}_2\text{COHSO}_3\text{Na}$, sometimes produce transient beneficial effects but after short storage periods the extracted products rapidly deteriorate, increasing in color and viscosity, and often the end result of the addition of these other compounds is actually deleterious rather than beneficial.

Example 1

A tar obtained by the low temperature carbonization of lignite was distilled into the following fractions:

	Fraction, boiling range, ° C.	Volume, Percent
20	150°-200°	7.7
25	200°-250°	13.9
	250°-300°	11.9
	300°-350°	13.2
	350°-400°	11.9
35	pitch	41.5

Extraction tests on the first five of these fractions, employing an aqueous solution of 5% potassium hydroxide with and without an added 1% by weight of sodium hydrosulfite ($\text{Na}_2\text{S}_2\text{O}_4$) were carried out. After phase separation the cresylates (aqueous layers containing potassium salts of the tar acids) were stored several days after which they were inspected for coloration. The results of this inspection are tabulated in the table below:

	Fraction, boiling range, ° C.	Appearance of cresylate layer	
		Extraction in presence of $\text{Na}_2\text{S}_2\text{O}_4$	Extraction without $\text{Na}_2\text{S}_2\text{O}_4$
40	150°-200°	colorless	reddish brown.
	200°-250°	do	deep red-brown.
45	250°-300°	do	Do.
	300°-350°	yellow	dark brown.
	350°-400°	do	Do.

Similar extraction tests using sodium sulfite Na_2SO_3 , sodium bisulfite NaHSO_3 , and sodium sulfoxylate $\text{H}_2\text{COHSO}_3\text{Na}$ were conducted. Although the cresylates initially obtained were somewhat lighter in color than those obtained with a straight caustic solution, they darkened rapidly on standing and furthermore formed dark precipitates indicating reaction of the reducing agent with substances present in the cresylate.

Example 2

A distillation fraction boiling between 150° and 300° C. of a tar obtained from the low temperature carbonization of lignite was extracted with an aqueous solution of 5% KOH containing 1% $\text{Na}_2\text{S}_2\text{O}_4$. A similar fraction was extracted with a 5% aqueous solution of KOH without any added hydrosulfite. In each case, the alkaline extract was back washed with benzene, acidified with dilute sulfuric acid, and the tar acids recovered by extraction with ether.

The tar acids extracted by the caustic solution containing added $\text{Na}_2\text{S}_2\text{O}_4$ were light yellow in color, and did not darken upon standing. The acids extracted in the absence of $\text{Na}_2\text{S}_2\text{O}_4$ were reddish brown in color, and became progressively darker upon storage.

Example 3

A distillation fraction boiling between 300° and 400° C. of a tar obtained from the low temperature carbonization of lignite was refluxed in a benzene solution over solid sodium bicarbonate for several hours. The mixture was filtered, and the filtrate divided into two portions. One portion was treated with an aqueous solution containing 5% KOH and 1% Na₂S₂O₄, and the other with 5% KOH without the addition of Na₂S₂O₄. The tar acids were recovered from the alkaline extracts by acidification of the extracts with dilute sulfuric acid and extraction with ether.

During the caustic extraction, the portion extracted in the presence of Na₂S₂O₄ underwent phase separation readily, both phases during the extraction were light in color, and there was no perceptible precipitation. During the extraction in the absence of added Na₂S₂O₄, both phases were dark and noticeable precipitation of insoluble material occurred. The tar acids extracted in the presence of added Na₂S₂O₄ were recovered as a mobile liquid of relatively low viscosity, while those extracted without the addition of Na₂S₂O₄ had an undesirably high viscosity.

Example 4

The tar acids produced in Examples 2 and 3 by extraction in the presence of sodium hydrosulfite were combined and distilled to a vapor end point of 210° at 10 mm. The tar acids produced in Examples 2 and 3 by extraction without the use of sodium hydrosulfite were combined and distilled in a similar manner. The distilled tar acids which had been extracted in the presence of sodium hydrosulfite were light in color and did not darken after several weeks storage. The tar acid distillate which had been extracted without the use of the hydrosulfite was initially darker in color and became progressively darker upon storage.

Example 5

Several fractions from a coal hydrogenation oil produced by the hydrogenation of a bituminous coal under a pressure of 7500 pounds per square inch and at a temperature of about 850° F. were extracted with an aqueous solution containing 10% sodium hydroxide and 2% by weight of sodium hydrosulfite. Similar fractions were extracted with a 10% sodium hydroxide solution without added sodium hydrosulfite. After phase separation, the cresylate layer was inspected for coloration. The following results were obtained:

Fraction, boiling range, ° F.	Appearance of cresylate layer	
	Extraction in presence of Na ₂ S ₂ O ₄	Extraction without Na ₂ S ₂ O ₄
81°-380°	yellow	brown
210°-450°	amber	dark brown
348°-645°	do	black opaque

The invention has general application for the extraction of tar acids from the relatively crude mixtures in which they are ordinarily found, such as from petroleum, from products resulting from the high or low temperature carbonization of coal, or from products resulting from the hydrogenation of coal. As used herein, the term coal includes coals of all ranks including particularly bituminous, sub-bituminous, lignites, brown coals and cannel coals. Phenol-containing products of the carbonization of peat, wood, and similar materials could also be treated in accordance with the invention. The use of hydrosul-

site during the extraction step is particularly useful in connection with the recovery of tar acids from the products of the low temperature carbonization of coal, especially from the low temperature carbonization products of the lower rank coals such as lignite. These low temperature tars apparently contain a greater amount of material which undergoes undesirable side reactions during caustic extraction than do high temperature tars.

If desired, other precautions may be taken in addition to the use of the alkali soluble hydrosulfite to prevent undesirable side effects during the caustic extraction. For example, by conducting the extraction in an oxygen-free atmosphere, further improved results can be obtained.

By operation in accordance with the invention, the final tar acid products are usually recovered in greater yields and are often substantially improved in marketability. They are generally colorless or only slightly colored, and of low viscosity, whereas those produced in accordance with conventional procedures are often opaque or highly colored, and of relatively high viscosity. These improvements are obtained without introducing an additional stage in present tar refinery practice, and with the use of only small amounts of a relatively inexpensive reagent.

It is to be understood that the above description, together with the specific examples and embodiments described, is intended merely to illustrate the invention, and that the invention is not to be limited thereto, nor in any way except by the scope of the appended claims.

I claim:

- 30 1. A method for recovering tar acids from materials selected from the group consisting of coal carbonization products and coal hydrogenation products which comprises extracting said products with an aqueous caustic solution containing from .2% to 3% of sodium hydrosulfite.
- 35 2. A method for recovering tar acids from the products of the low temperature carbonization of coal which comprises extracting said products with an aqueous caustic solution containing from .2% to 3% of sodium hydrosulfite.

- 40 3. A method for recovering tar acids from products of the low temperature carbonization of lignite which comprises extracting said products with an aqueous caustic solution containing from .2% to 3% sodium hydrosulfite.

- 45 4. A method for recovering tar acids from materials selected from the group consisting of coal carbonization products and coal hydrogenation products which comprises extracting said products with an aqueous caustic solution containing from 0.2% to 3% of sodium hydrosulfite, acidifying the caustic solution with a weak mineral acid, and extracting the resulting tar phase with ether.

- 50 5. A method for recovering tar acids from the materials selected from the group consisting of coal carbonization products and coal hydrogenation products which comprises extracting said products with an aqueous caustic solution containing from 0.2% to 3% of a compound selected from the group consisting of the hydrosulfites of sodium, potassium, and ammonium, acidifying the caustic solution with a weak mineral acid, and extracting the resulting solution with ether.
